WATER BOTTLE CASE

Carl E. Frahm and Shirley E. Frahm, both of 1428 Oak
Meadow Road, Arcadia, Calif. 91006

Filed Apr. 30, 1970, Ser. No. 22,737

Term of patent 14 years

Int. Cl. D9—04

U.S. Cl. D9—177

FIG. 1.

FIG. 2.

FIG. 6.

FIG. 2.

FIG. 5.

FIG. 3.

FIG. 4.

FIG. 1 is a perspective view of a water bottle case showing our new design.

FIG. 2. is a top plan view thereof;

FIG. 3 is an elevation of the side opposite that shown in FIG. 1;

FIG. 4 is an elevation of another side opposite that shown in FIG. 1.

FIG. 5 is a bottom plan view thereof;

FIGS. 6 and 7 are sectional views taken substantially as indicated by the corresponding lines 6—6 and 7—7 in FIG. 3.

We claim:

The ornamental design for a water bottle case, as shown.
